UNITED STATES PATENT OFFICE.

JESSE MONROE COFFMAN, OF MONTALVO, CALIFORNIA.

WATER-DISTILLING APPARATUS.

SPECIFICATION forming part of Letters Patent No. 732,831, dated July 7, 1903.

Application filed October 30, 1902. Serial No. 129,451. (No model.)

To all whom it may concern:

Be it known that I, JESSE MONROE COFFMAN, a citizen of the United States, residing at Montalvo, in the county of Ventura and 5 State of California, have invented certain new and useful Improvements in Water-Distilling Apparatus; and I do declare the following to be a full, clear, and exact description of the invention, such as will enable others skilled 10 in the art to which it appertains to make and use the same.

My invention is an improved water-distilling apparatus especially adapted for domestic purposes; and it consists in the peculiar 15 construction and combination and arrangement of devices hereinafter described and claimed.

The object of my invention is to provide a simple, efficient, and comparatively inexpensive 20 water-distilling apparatus for domestic use which is especially adapted to be used in connection with an ordinary cook-stove or range for economically distilling water for drinking purposes and for ridding the water 25 of the gases given off by particles of organic, vegetable, or animal matter, hence rendering such water when distilled both palatable and healthful.

In the accompanying drawings, Figure 1 is 30 a side elevation of a water - distilling apparatus embodying my improvements, showing the heating-coil disposed in one side of the fire-box of a range, the latter being shown in section. Fig. 2 is a detail elevation, partly 35 in section, of the purifier and condenser-coil. Fig. 3 is a detail longitudinal sectional view of the separator; and Fig. 4 is a detail top plan view of the same, partly in section.

In the embodiment of my invention here 40 shown I provide a heating-coil 1, in which the water is boiled, which heating-coil is disposed in one side of the fire-box of a stove or range, so that the same is heated by the fire used for ordinary cooking purposes. A reservoir 2 or 45 other source of water, which is here shown as a tank supported at a suitable elevation above the heating-coil, is connected to the latter by a feed-pipe 3. In practice the tank or reservoir should be provided with a water-gage, 50 as here shown, and with a float-valve to prevent the same from being overflowed. A steam-pipe 4 leads from the heating coil or

boiler to a separator 5. This separator is a chamber of enlarged capacity as compared with the steam-pipe 4 and is preferably of the 55 form shown in Figs. 3 and 4, having a lateral prolongation 6 on its rear side directly opposite the opening in the front side thereof with which the steam-pipe 4 communicates. The separator is also preferably provided on 60 its lower side with a vertically-depending prolongation 7, to which is coupled a water-return pipe 8, the latter serving to return water from the separator to the feed end of the heating coil or boiler 1. A steam-pipe 9 leads from the upper side of the separator and communicates with a condensing-coil 10. In practice the condensing-coil is disposed in the outer air, but the same should be shielded from the direct rays of the sun. A service-pipe 11 leads 65 from the condensing-coil into the house. I also provide a vertically - disposed pipe 12, which rises from the steam-pipe 9 at the point where the latter is coupled to the condensing-coil, and the said pipe 12 is provided at its 70 upper end with a cap 13, forming a closure therefor, which cap is provided with an orifice 14, in practice about one thirty-second of an inch in diameter, for the escape of gases 75 arising from the presence of organic matter 80 in the water. These gases being lighter than the steam separate from the latter at the base of the purifier and escape through the opening 14, while the steam passes from pipe 9 into the coil 10 in the outer air, in which coil 85 the steam is condensed, the resulting distilled water being fed from the condensing-coil to the service-pipe 11.

The commingled steam and water are discharged from the boiler or the heating-coil 1 90 through the pipe 4 into the separator. The construction and capacity of the latter are such as to cause the steam to separate from the water, the latter returning through the pipe 8 to the feed end of the coil 1 and the steam 95 passing from the separator up through the pipe 9, as hereinbefore stated.

To enable the apparatus to be drained, I provide a draw-off faucet 15, which is here 100 shown as coupled to the water-supply pipe 3.

In practice the reservoir may be supplied from the waterworks when the apparatus is used in a city; otherwise the reservoir may be filled in any suitable manner.

From the foregoing description, taken in connection with the accompanying drawings, the construction, operation, and advantages of my invention will be readily apparent, it is thought, without requiring a more extended explanation.

Various changes in the form, proportion, and the minor details of construction may be resorted to without departing from the principle or sacrificing any of the advantages of my invention.

Having thus fully described my invention, what I claim as new, and desire to secure by Letters Patent, is—

15 In apparatus of the class described, the combination with a boiler of a separating-chamber having a lateral extension 6 and a depend-

ing extension 7, a steam-pipe leading from the boiler to the separator and discharging commingled steam and water into the latter 20 at a point opposite the lateral extension, a water-return pipe leading from the depending extension 7 of the separating-chamber back to the boiler, a condenser, and a steam-pipe leading from the upper portion of the 25 separating-chamber to the condenser, substantially as described.

In testimony whereof I have hereunto set my hand in presence of two subscribing witnesses.

JESSE MONROE COFFMAN.
